UNITED STATES PATENT OFFICE

121,639

DESIGN FOR TEXTILE FABRIC OR SIMILAR ARTICLE

Selma Schiffman, Brooklyn, N. Y.

Application May 3, 1939, Serial No. 84,763

Term of patent 3½ years

To all whom it may concern:

Be it known that I, Selma Schiffman, a citizen of the United States and a resident of Brooklyn, county of Kings and State of New York, have invented a new, original, and ornamental Design for Textile Fabric or Similar Article, of which the following is a specification, reference being had to the accompanying drawing, forming a part thereof, wherein:

The figure of the drawing is a face view of a piece of textile fabric showing the design, the angle lines on the drawing encompassing a repeat motif thereof.

I claim:

The ornamental design for textile fabric or similar article, as shown and described.

SELMA SCHIFFMAN.
